Primary Examiner—Mitchell I Siegel

(74) *Attorney, Agent, or Firm*—Banner & Witcoff, Ltd.

(57) **CLAIM**

The ornamental design for a golf club, as shown and described.

DESCRIPTION

FIG. 1 is a rear perspective view of a first embodiment of a golf club showing our new design;

FIG. 2 is a rear view thereof;

FIG. 3 is a heel-end view thereof;

FIG. 4 is a toe-end view thereof;

FIG. 5 is a rear perspective view of a second embodiment of a golf club showing our new design;

FIG. 6 is a rear view thereof;

FIG. 7 is a heel-end view thereof;

FIG. 8 is a toe-end view thereof;

FIG. 9 is a rear perspective view of a third embodiment of a golf club showing our new design;

FIG. 10 is a rear view thereof;

FIG. 11 is a heel-end view thereof; and,

FIG. 12 is a toe-end view thereof.

The broken line showing of the remainder of the golf club is for environmental purposes only and forms no part of the claimed design.

1 Claim, 6 Drawing Sheets
